UNITED STATES PATENT OFFICE

ARTHUR E. BELLIS, OF BRANFORD, CONNECTICUT

ELECTRIC FURNACE

Application filed August 27, 1930. Serial No. 478,049.

This invention relates to an improved electric furnace for heat treating metals, and has for its general object and purpose to provide certain improvements in a furnace of this type as disclosed in my pending application for patent Serial No. 326,002, filed December 14, 1928.

In my pending application there is disclosed a furnace embodying a metal pot or crucible to contain salt materials together with an electrode extending into said pot and the electrode and the pot wall being connected with a source of alternating electric current whereby the solid salt materials may be fused and the pot wall maintained at a comparatively low temperature. In the use of such furnace, in order to initiate melting of the salt materials, it was necessary to either apply a torch flame thereto or otherwise initially heat the material independently of the electrode.

It is the primary object and purpose of my present invention to provide means whereby the initial heating of the salt may be facilitated, and the necessity of using a torch, electric arc, or other auxiliary heating means obviated.

In one practical embodiment of the invention, I provide two spaced electrodes adjustably mounted to extend into the pot or crucible and connected with the primary and secondary windings respectively, of a suitable transformer for alternating electric current. These electrodes are connected at their lower ends by a high resistance wire. This wire being heated to a high temperature, quickly melts the salt materials in the vicinity thereof, the transference of heat from the electrodes throughout the remainder of the salt material being thereby greatly facilitated, and expediting complete fusion of the salt to the desired liquid condition. Also by means of this high resistance wire, during periods when the furnace is not being used, the current supply may be reduced and the salt material kept at a very low temperature, with a small volume of the salt surrounding the resistance wire maintained in a liquid condition. Thus, it will be apparent that

the furnace may be very economically operated.

With the above and other objects in view, the invention consists in the improved electric furnace and in the form, construction and relative arrangement of its several parts as will be hereinafter more fully described, illustrated in the accompanying drawings, and subsequently incorporated in the subjoined claims.

In the drawings, wherein I have disclosed one simple and practical embodiment of the present invention, and in which similar reference characters designate corresponding parts throughout the several views,—

Figure 1 is a vertical sectional view through the furnace, illustrating one practical embodiment of the present invention.

Fig. 2 is a top plan view thereof.

Fig. 3 is a fragmentary vertical sectional view showing a slightly modified form of the device; and

Fig. 4 is a vertical section illustrating another embodiment of the invention.

Referring in detail to the drawings, 5 designates the pot or crucible of the furnace, which may be produced from steel, chrome iron, or other metal alloy, either wrought or cast. The bath to be used as a heat transfer medium preferably consists of a number of metallic salt components so selected and mixed as to produce a bath, which when fluid, is of low viscosity and may be heated to a desirably high temperature without fuming. For the heat treatment of high speed steel tools, this bath should be capable of attaining a temperature of 2500° without vaporization. There are well known salt materials of this character now on the market. However, since the subject matter of the present application is not concerned with any specific salt bath composition, it will not be herein further referred to in detail.

As shown in the drawings, the pot is preferably first encased in the fire brick indicated at 6, and this fire brick setting is in turn encased within a relatively thick walled insulating structure 7. It will be understood, however, that the form of the bath receiving pot or crucible and the insulating means

therefor, as shown in the drawings is purely suggestive and not specifically essential to my present purpose.

In conjunction with the metal pot 5, I employ the two spaced electrodes 8, each of which is vertically adjustable upon a suitable supporting arm 9 of electrical conducting material mounted in an insulating base 10 which may be suitably fixed upon the fire brick setting 6. These electrodes 8 extend downwardly into the pot 5 in parallel relation to each other and into the salt bath materials which have been placed therein.

Electric current is supplied to the electrodes 8 at proper voltage, the value thereof depending upon the size and type of the pot 5. This necessitates the use of a transformer 11 as a part of the installation, alternating current being supplied to the primary of the transformer as at 12, and in which a suitable automatic control means may be located.

The transformer to be used in connection with the type of pot 5 shown in the drawings is rated at 220 to 11 volts, 20 kva. when using 20 kilowatts. The current input at full power is 1820 amperes. The secondary of the transformer is connected by the conductors 13 and 14 to the supporting arms 9 of the respective electrodes 8.

The lower ends of the spaced electrodes 8 are connected by the high resistance wire shown at 15, end portions of this wire being coiled around the respective electrodes and suitably fixed thereto.

In the use of the furnace, the solid salt materials are placed in the pot or crucible in sufficient quantity to extend well above the high resistance wire 15. Upon closing the current supply circuit, the current passes through the spaced electrodes 8 and the resistance wire 15 so that this wire becomes more or less incandescent, and immediately melts the solid salt material surrounding the same to a liquid condition. In view of the fact that this liquid salt is of very low viscosity, there would be a rapid transference of heat so that the remainder of the solid salt will be very quickly fused by the heat radiated from resistance wire.

It will be apparent that the heat efficiency of an electric furnace of the above description will be very high, over 90% of the current power input being developed as heat directly in the bath material.

By the use of a suitable cover for the pot or crucible and the thick insulating walls therefor, the heat losses may be kept down to a very low value. In the illustrated furnace, 10 kilowatts is sufficient to maintain the temperature of the

bath with a normal amount of removal of the pot cover, thus leaving 10 kilowatts available to heat the work. By heating the bath material in this manner, the necessity of maintaining the walls of the pot or crucible

and its external surroundings at a higher

temperature than the bath material is eliminated. In the use of oil or other fuels for generating heat externally applied to the wall of the crucible, the pot wall must necessarily attain a higher temperature than the bath, in order to raise the temperature of the bath to the desired point. Thus, the structure of the pot or crucible rapidly deteriorates or is burned out so that pots must be frequently replaced. In my new furnace, on the other hand, the heat is initially generated directly in the bath materials. And therefore, there is a descending temperature gradient from the dissolved salt bath materials outwardly through the wall of the pot. Accordingly, since this pot may be mounted in a heat insulating support, the thickness of which need be limited only by the available floor space, great economy in power consumption may be realized with ample external protection to the pot to the oxidizing effects of the atmosphere. By reason of the relatively low pot temperature for any given bath temperature, the useful life of the pot is prolonged almost indefinitely. The heating of the salt bath materials by means of an electric furnace of this description, thus achieves ultimate simplicity with maximum economy both in the initial installation and in operation and maintenance costs.

By vertically adjusting the electrodes 8 to regulate their depth of penetration into the salt materials, the heat input may be regulated as required to maintain a desired bath temperature. Notwithstanding the fact that the solid salt material is an insulator, by the provision of the high resistance wire 15 connecting the electrodes, the reduction of the salt to a liquid condition is quickly accomplished without necessitating the use of other additional heating mediums, such as a torch, electric arc or the like. During periods when the furnace is not being used, the electric current supply may be greatly reduced to hold the bath at a very low temperature, while a small volume of the bath material in the immediate vicinity of the resistance wire 15 is maintained in a liquid condition. Thus, the re-fusing of the salt when the furnace is to be again used will be greatly expedited. The current consumption over the period of shutdown of the furnace and the expenses incident thereto will be comparatively trivial.

The electrodes 8 may be of the same material as the wall of the pot or crucible 5, or of any other suitable materials which will not release impurities into the bath solution. The salt bath material is of such composition that it will be neutral to the metal to be treated so that chemical reactions between the bath material and metal articles at high temperatures which would either carburize or decarburize the metal surfaces will not occur. I am aware of the fact that such salt baths have been commercially used in this art and

have been heated either by means of electric resistance coils surrounding the pot or container, or on the other hand, by means of an electrode supplied with direct current. In the latter case, electrolysis and rapid deterioration of the bath materials results. When a non-metallic refractory pot is used, any attempt to heat the bath to the higher temperatures such as those required for the hardening of high speed tool steels, results in reactions between the bath material and the refractory material in the pot resulting in heavy contamination of the bath and the carburization or pitting of the steel objects being treated. Since such refractory pots have a very short life, frequent replacements thereof, greatly adding to the operating and maintenance costs of the furnace are required. The use of electrical resistance coils exteriorly of the pot are not commercially feasible for the heating of the bath to the higher temperatures. In order to maintain the bath temperature, the wall of the pot or crucible must be kept at an excessively high temperature since the heat is transmitted from the coil through the pot wall to the bath materials. The rapid deterioration and breaking down of the pot or container and contamination of the bath solution would inevitably result. This fact alone makes the use of such resistance coils entirely impractical without regard to the expense incident to the initial installation of such heating equipment and the frequent replacement of the coils owing to the excessively high resistance required.

As shown in Fig. 3 of the drawings, in lieu of the resistance wire surrounding the lower end of the electrodes I may provide the resistance 15' in the form of a flat metal strip having its intermediate portion formed into a plurality of rectangular convolutions 15^a disposed in the same vertical plane, the upper and lower ends of the strip being laterally extended in opposite directions, and suitably connected to the respective electrodes 8. This form of the resistance strip, insures a high degree of rigidity, even when the strip is heated to incandescence. Usually, however, it is only necessary to heat the resistance to a glowing red heat in order to fuse the salt materials.

In Fig. 4 of the drawings, I have illustrated another modified form of furnace, in which only a single electrode 8' is used. In this case, the upper end of the metal pot is formed with a flange extension 5' to which the conductor 13' from the transformer is connected. The other conductor 14' is connected to the electrode supporting arm 9', said arm being adjustably mounted in the spaced guides 16, suitably secured to one side of the furnace casing and insulated therefrom.

The resistance coil 15b is attached to the lower end of the electrode 8' and extends below the same and into a body of lead indi-

cated at L which is placed at the bottom of the furnace pot. Thus, in this case, it will be understood that the circuit is closed through this body of lead, the wall of the pot and its flange extension 5 to which conductor 13' is connected. The single electrode 8' in this case may be arranged adjacent to one side of the pot so that greater pot capacity is attained for receiving the metal objects to be treated.

My new furnace for heating such high temperature salt baths as herein described, entirely overcomes the serious objections to prior art furnace constructions of the type above referred to, and provides an electric furnace of very simple construction, which in both its initial installation and maintenance and operating costs will be comparatively inexpensive, while accurately reproducible results in the heat treatment of metal articles of similar form and size and without surface blemish may be obtained.

From the foregoing description, it will be seen that I have provided a highly efficient and serviceable electric furnace for use in heat treating metals which in addition to the numerous advantages above referred to also possess the other collateral merits of the use of electrical heat, viz., compactness, convenience, safety, and flexibility etc. I have herein illustrated and described a practical embodiment of my present improvements which has given excellent results in commercial use. Nevertheless, it will be understood that the essential features of the present disclosure might also be embodied in various other structural forms, and I accordingly reserve the privilege of resorting to all such legitimate changes in the form, construction and arrangement of the several elements as may be fairly embodied within the spirit and scope of the invention as claimed.

I claim:

1. In combination with a furnace crucible adapted to receive soluble bath materials, electrical heating means including spaced electrodes having one of their ends positioned within the crucible, and a high resistance conductor extending between said electrodes and having portions coiled about said ends thereof.

2. In combination with a furnace crucible adapted to receive metal heat treating salts, electrical means for fusing the salt materials including spaced electrodes, means for vertically adjusting said electrodes to position the same with respect to the bottom of the crucible, and a high resistance wire having parts coiled about the lower end of each electrode and bridging the space therebetween.

3. In combination with a furnace crucible of electrically conductive metal, electrical heating means including an electrode extending vertically into the crucible adjacent one side thereof, a resistance connected to the

lower end of the electrode, means for connecting the electrode to one side of an electrical current supply circuit, means for connecting the wall of the crucible to the other side of the supply circuit, and a body of electrically conductive metal in the bottom of the pot fusible at relatively low temperature and into which the lower end of said resistance extends.

4. In combination with a furnace crucible adapted to receive salt materials of high melting point, electric means for fusing the salt materials including a pair of electrodes spaced apart for a distance appreciably less than the diameter of the crucible, means supporting said spaced electrodes within the crucible and at one side of the central region thereof, means for vertically adjusting and rigidly securing said electrodes against movement with respect to the crucible, and 20 a high resistance conductor of small cross section with respect to the electrodes connected with the latter and sustained in closely juxtaposed relation thereto out of contact with the crucible walls.

25 In testimony that I claim the foregoing as my invention, I have signed my name hereto.

ARTHUR E. BELLIS.
